UNITED STATES PATENT OFFICE.

FREDERICK C. BAXTER AND WILLIS H. KERN, OF BEVELIDERE, ILLINOIS.

FUNNEL.

1,219,222.

Specification of Letters Patent. Patented Mar. 13, 1917.

Application filed May 13, 1916. Serial No. 97,424.

To all whom it may concern:

Be it known that we, FREDERICK C. BAXTER and WILLIS H. KERN, citizens of the United States, and residents of Belvidere, in the county of Boone and State of Illinois, have invented certain new and useful Improvements in Funnels, of which the following is a specification.

The present invention relates to new and useful improvements in valve-controlled funnels and has for its primary object the provision of a funnel having novel float operated means associated therewith for controlling the flow of liquid through the funnel.

Another object of our invention is to provide a funnel of the class described which is adapted to be placed in a receptacle to be filled, the funnel having means associated therewith whereby when liquid in the receptacle reaches a predetermined height the flow of liquid through the funnel will be automatically stopped.

A further object of our invention is to provide manually controlled means for opening the valve against the action of the float control.

Other objects and advantages to be derived from the use of our improved funnel will appear from the following detail description and claims, taken with an inspection of the accompanying drawing, in which:

Figure 1 is a vertical sectional view through a funnel embodying the improvements of our invention;

Fig. 2 is a plan view with the supporting bracket for use in connection with the funnel spout; and

Fig. 3 is an enlarged vertical sectional view of the funnel spout adjacent the valve means showing the latter in closed position.

Referring more particularly to the drawing, wherein similar characters of reference designate like and corresponding parts throughout the various views, 1 designates the body of our improved funnel and 2 the spout.

The controlling mechanism of our invention and the valve means comprise a valve member of the plate type designated 3 and hinged at 4 on a partition 5 extending approximately half-way across the spout 2. A closing wall 6 extending vertically in the spout serves to support said partition 5 and to carry a vertically arranged tubular mem-

ber 7, said wall being provided with a lateral extension 8 for the purpose of supporting said tube 7. The tube 7 extends above the normal height of liquid in the body 1 and carries a vertically arranged rod 9 having a handle 10 on the upper end thereof and a head 11 on the lower end thereof. The rod 9 is provided with a projection 12 approximately intermediate its length for engagement with a coil spring 13, the lower end of the latter engaging the extension 8 for a purpose which will hereinafter appear.

A second wall 14 is provided, the same extending downwardly in the spout 2 from the partition 5 thereby forming a float chamber 15 in which is vertically movable a float 16. We provide means for intermittently connecting the float with the valve. Of course, it is to be understood that the float carries the rod 18 formed with an eye 19 at the upper end thereof.

A connecting member is carried by the valve 3 and is formed of a single strand of wire 20 bent up in itself intermediate its ends to provide divergent portions 21 and 22, said strand of wire being laterally bent to form a loop 23 for engagement intermittently with the eye 19 formed on the float body. The strand of wire 20 is connected at 24 to the valve 3, said strand being formed with curved portions 25, said portions 25 being connected together as at 26, thereby forming a bracing truss-like structure.

In operation as the float descends the motion is transmitted therefrom to the valve 3 by virtue of the engagement of the loop 23 with the eye 19. This action causes the valve 3 to open permitting the contents of the funnel to pass through the spout into a suitable container. As the container fills, the float rises, thereby permitting the valve to be closed. When the funnel is removed from the container of course the weight of the float would normally tend to reopen the valve. However, prior to this the eye 19 has disengaged itself from the loop 23 and the float is then permitted to descend to the position shown in Fig. 1. In this position the eye 19 engages the lowermost curved portion 25 of the strand of wire 20, thereby maintaining the valve in closed position. A partition 27 is provided through which the rod 18 operates.

When the funnel is placed in a container and filled with a liquid it is of course nec-

essary that the valve be open. For this purpose the rod 9 and the enlargement 11 carried thereby have been provided. It will be seen that by depressing the rod 9 the enlargement 11 will engage the loop 23 opening the valve 3 and bringing the loop downwardly into engagement with the eye 19 whereupon the operation hereinbefore set forth is repeated.

10 We regulate the depth to which the spout 2 is inserted into a receptacle by means of a strap 22 surrounding the spout 2 and having a plurality of radial extensions 23. The free ends of the strap are connected as at 24 and the extensions 23 are adapted to engage a receptacle, such as a bottle or the like adjacent the inlet opening thereof. By moving the adjusting member up and down on the spout 2 the depth to which the same extends into 15 the receptacle may be regulated.

It is thought that the operation of our invention will be clear from the foregoing description, however, we desire to lay particular stress on the peculiar arrangement of the 20 arcuate extension 17 carried by the valve. This extension protrudes through a suitable opening in the wall 14 and when the valve is in closed position, as shown in Fig. 3, the free end of the extension 17 adjacent the 25 loop 23 is located beneath the head 11. It will be seen that when the float rises the valve 3 will be closed, and should it be desired to open the valve against the action of the float the rod 9 may be depressed bringing the head 11 into engagement with the 30 loop 23 opening said valve. We also desire to lay particular stress on the extremely simple construction of our improved funnel, and it will be seen that by the provision of the 35 screen 20 we prevent foreign particles from reaching the valve which might tend to clog the same and prevent free operation. It will also be readily apparent that the spring 40 serves to return the rod 9 to normal position after depression.

From the above description taken in connection with the accompanying drawing, it is thought that a clear and comprehensive understanding of the construction, operation 45 and advantages of our invention may be had, and while we have shown and described our invention as embodying a specific structure, we desire that it be understood that we may make such changes in said structure as 50 do not depart from the spirit and scope of the invention as claimed.

Having thus fully described our invention, what we claim as new and desire to secure by Letters Patent, is—

1. A funnel of the class described, including a body having a spout extending therefrom, a vertical partition in said spout, and a horizontal partition extending from said vertical partition, a valve operable in the horizontal partition to stop the flow of liquid through said spout, an extension carried by said valve, said extension passing through an opening in said vertical partition, a float, means connecting said float with said extension, and manually operable means carried by the body of the funnel for engagement with said extension to open the valve against the action of the float. 60

2. A funnel of the class described, including a body having a spout extending downwardly therefrom, a vertical partition in said spout, a horizontal partition extending from said vertical partition, a valve pivotally arranged on the horizontal partition, a strand of wire bent intermediate its ends to form a loop, one end of said wire being connected to the bottom of the said valve, the other end engaging the side of the first mentioned portion to form a bracing means therefor, a float, an extension carried by said float having an eye hook formed on the end thereof and adapted to be slidably mounted on the said wire strand member to operate the said valve. 75

3. A funnel of the class described, including a body having a spout extending therefrom, a vertical partition in said spout, a horizontal partition extending therefrom, said vertical partition forming a float chamber in combination with the spout wall, a valve operable in the first said partition, an extension carried by the said valve, a float operable in said float chamber and connected to said extension, a lateral extension formed on the vertical wall having an aperture in the said extension, a rod slidably mounted in the said tube and the said aperture, a handle formed on one end and a head on the other end of the said rod, a projection formed thereon intermediate its length for engagement with a coil spring, and the other end being in engagement with the lateral extension for a purpose specified. 90

In testimony whereof, we affix our signatures hereto.

FREDERICK C. BAXTER.
WILLIS H. KERN.
